DOOR HINGE

Filed Aug. 31, 1928.

FIG. 1.

FIG. 2.

FIG. 3.

Inventor:

A. Arocha,

By Robert Burns,

Attorney.

UNITED STATES PATENT OFFICE.

ARMANDO AROCHA, OF CHICAGO, ILLINOIS.

DOOR HINGE.

Application filed August 31, 1928. Serial No. 303,138.

This invention relates to door and like hinges of the single pintle type, and this improvement has for its object:

To provide a structural formation and combination of the hinge parts adapting the same for surface application to a door and door jamb, with the consequent avoidance of mortices or receiving recess for the leaf portions of the parts. And further, to provide means whereby an effective bracing and reinforcing of the jamb member of the hinge is attained and its substantial attachment in place, is effected, all as will hereinafter more fully appear.

15 In the accompanying drawing:

Fig. 1, is a top view of the hinge parts in the preferred form of the invention, with portions of the door and door jamb shown in section.

20 Fig. 2, is a side elevation of the assembled hinge members.

Fig. 3, is a front elevation of the same.

Like reference numerals indicate like parts in the different views.

25 In this invention the door leaf or plate 1, and the jamb leaf or plate 2 are formed with tubular pivot ears or knuckles 3, and 4, through which the pivot pin or pintle 5 passes to pivotally connect said parts together, as usual in the single pintle type of door hinges.

The door leaf or plate 1, is preferably of right angle shape comprising a narrow flange 1' carrying the pivot knuckles 3 of the leaf 1, 35 and a wide flange 1'' by which the leaf 1 is secured to the surface of the door 6 by screws or like fastening means.

The door jamb leaf or plate 2 of the hinge, in the present improvement, has its main portion of a thin plate formation formed with a longitudinal abutting shoulder or offset 7 a short distance from the pivot knuckles 4 of the leaf or plate, with said shoulder or offset 7 formed by an added thickness in leaf 45 or plate between said shoulder and said knuckles.

With the described formation, the shoulder or offset 7 is adapted to have abutting contact against an edge or corner of the door jamb 8, with the thin main portion of the

leaf or plate resting against the surface of the side face of said jamb and secured thereto by screws or similar fastening means.

Another and material feature of the improvement, comprises an auxiliary leaf or plate 9 formed with knuckles 10 for engagement with the pivot pintle 5, and adapted to assume a right angle relation to the aforesaid jamb leaf or plate 2 and be secured to the surface of the casing 8' of the door jamb 8. 60 With the described arrangement the auxiliary leaf or plate 9 forms a very effective brace for the aforesaid jamb leaf or plate 2, and strengthens the same in a substantial manner.

In the construction shown in the drawing, 65 the auxiliary bracing leaf or plate 9, is formed as a part separate from the jamb leaf or plate 2 of the hinge, in that such formation is adapted to the manufacture of the hinge from sheet metal by suitable punch and die operations. It is however within the scope of the invention to make said auxiliary bracing leaf 9, integrally with and a fixed part of the jamb leaf or plate 2, where the structure is formed of cast metal. 75

Having thus fully described my invention, what I claim and desire to secure by Letters Patent is:—

In a door or like hinge, a door leaf adapted for surface attachment to a face of the door 80 and comprising a main attaching plate having angular end extensions formed with pivot knuckles on their free ends, a door jamb leaf having pivot knuckles and formed with a longitudinal abutment shoulder a short distance from its pivot knuckles, an auxiliary bracing leaf having pivot knuckles in side relation to the body of the leaf, said bracing leaf being in angular relation to the jamb leaf and adapted for attachment to the surface of the casing of the door jamb, and a pivot pintle engaging the aforesaid knuckles. 85

In testimony whereof I hereunto affix my signature.

ARMANDO AROCHA. 95
